ATTYS.

UNITED STATES PATENT OFFICE.

FRANK JOSEPH POPE, OF KITCHENER, ONTARIO, CANADA.

HYDRANT-THAWING DEVICE.

Application filed February 10, 1925. Serial No. 8,229.

My invention relates to improvements in hydrant thawing devices and the object of the invention is to devise a simple and effective means for thawing out hydrants should they become frozen without the necessity of having to use cumbersome apparatus as is at present the case.

A further object is to devise an electric heating element which can be attached to the cap of the hydrant spout and which will extend into the air chamber in the hydrant, all as hereinafter more particularly described and illustrated in the accompanying drawing in which:

15 Fig. 1 represents an elevational view of the upper portion of a hydrant partly in section showing my device applied thereto.

Fig. 2 is an enlarged vertical section through a hydrant spout cap showing my heating element applied thereto, and

Fig. 3 is an enlarged view thereof.

Like characters of reference indicate corresponding parts in the different views.

1 is the hydrant and 2 is the air chamber therein. 3 is one of the hydrant spouts. 4 is a spout cap provided with a central orifice 5 through which extends the holder 6 upon which is mounted my electric heating element 7, said holder 6 being provided with a 25 plug 8 connected by the wires 9 with any electric light circuit.

The holder 6 is provided with an intermediate shoulder 9 which is adapted to engage a shoulder 10 on the ring 11 which is 30 adapted to extend over the holder and to be

secured to the inner face of the cap end by means of the screws 12.

When a hydrant is frozen a spout cap provided with my heating element is screwed onto the spout 3 in place of the ordinary cap 40 and the wires 9 connected to any suitable electric light circuit. Thus the air chamber 2 and the entire interior of the hydrant 1 is heated with the result that any ice around the valve of the hydrant is thawed out. 45

From the above description it will be apparent that I have devised a simple and effective means for thawing out hydrants which will be exceedingly effective in use and which can be readily carried from hydrant to hydrant. Moreover, I have constructed a device which will entirely do away with the cumbersome apparatus at present in use for this purpose. 50

What I claim as my invention is:—

A device for thawing hydrants comprising in combination, an externally threaded hydrant spout, a cap internally threaded and screwed onto the externally threaded spout of the hydrant, a horizontally disposed inwardly extending electric heating element, a holder for the electric heating element extending through the cap end and having a shoulder disposed intermediately of its length, a ring extending around the holder 60 and having an inwardly extending portion 65 engaging the shoulder on the holder, and means for securing the ring to the cap.

FRANK JOSEPH POPE.
